UNITED STATES PATENT OFFICE.

EDWARD H. KRUSE, OF FORT WAYNE, INDIANA.

ADJUSTABLE SWITCH-BOX.

989,854.

Specification of Letters Patent. Patented Apr. 18, 1911.

Application filed October 14, 1909. Serial No. 522,517.

To all whom it may concern:

Be it known that I, EDWARD H. KRUSE, a citizen of the United States, residing at Fort Wayne, in the county of Allen, in the 5 State of Indiana, have invented certain new and useful Improvements in Adjustable Switch-Boxes; and I do hereby declare that the following is a full, clear, and exact description of the invention, which will enable others skilled in the art to which it 10 pertains to make and use the same, reference being had to the accompanying drawings, which form part of this specification.

My invention relates to improvements in 15 adjustable switch boxes, especially designed for use in incandescent lighting.

It is well known that in setting switch boxes for new work the plasterers who follow up the electric wiring of a building seldom 20 get the plastering even or flush with the outer edge of the box, and therefore it is generally necessary to block up the switch box closing plate by means of washers, instead of mounting such plate squarely and firmly 25 upon the outer edge of the box.

The primary object of my present invention is to provide a cheap, simple and convenient switch-box so constructed as to admit of a limited lateral adjustment to compensate for different thicknesses of plastering, and to permit the mounting of the closing-plate firmly upon the adjacent edges of the switch-box and against the plastering.

My invention consists of a switch-box of 35 the usual form and dimensions, and provided upon two opposite sides thereof, preferably the top and bottom, with supporting slotted brackets between which the box has a limited adjustment to bring its outer edge 40 in proper relation to the plastering about the same; means for guiding the box in its adjustments; and means for moving it in or out at pleasure.

Similar reference numerals indicate like 45 parts throughout the several views of the drawings in which—

Figure 1 is a front elevation of my invention showing the usual ears for securing it in position, the bifurcated ends of the brackets in which the box slides, the screws in the bottom of the box for making the adjustment, and showing a plurality of the usual "knock outs" for the admission of the wires. Fig. 2 is a vertical section of the 55 same showing the brackets as fixed to the

lath, and showing by dotted outline how the box is adjusted inwardly to rest against the plastering of which a fragmentary view is shown. This view also shows the relative arrangement of the means for guiding the 60 box in its adjustments, and the means by which the adjustments are made. Fig. 3 is a plan view of one of the slotted supporting brackets between which the switch-box 1 is mounted and adjusted. Fig. 4 is a side view 65 of one of the adjusting screws, having thereon a form of split washer which I employ, and Fig. 5 is a detail of the washer. Fig. 6 shows a gang box for a plurality of switches, the lath on which it is fixed and the plastering upon which it abuts being shown in a fragmentary view, and the flush plate with its switch buttons being partly broken away.

The box 1, of proper size, contour and dimensions has the outer edge upon its upper 70 and lower sides provided with the usual or other proper over-turned ears 2, having a lateral perforation 3 for proper holding screws, not shown. Adjacent to the outer face of the upper and lower sides of the 75 box 1 are arranged the horizontal brackets 4 having their outer end bifurcated as shown in Fig. 3, and provided with the outwardly turned lugs 5 having suitable lateral perforations 6 for the screw 7 by 80 means of which the brackets are rigidly secured to the lath 8. The inner ends of the brackets are inwardly turned to form lugs 9 having lateral screw threaded openings 85 for the adjusting machine screws 10 which 90 are loosely mounted in lateral openings in the bottom of the box 1.

In use the heads of the screws 10 have washers 11. The heads of the screws 10 are kept firmly pressed to their position in use 95 by means of the lock nuts 12. Instead of employing the lock nuts 12 the screw 10 may have an annular groove therein near its head and a split washer clamped in the groove, the use of which avoids removal of 100 the screw from its operative position.

The brackets 4 are provided with a longitudinal slot 13 through which loosely pass the short screws 14 which are secured in suitable screw-threaded openings in the adjacent sides of the box. The head 15 of the screws 14 is of sufficient width to extend beyond the sides of the slots 13, as shown in Fig. 3, whereby the box 1 and its supporting brackets 4 are firmly held in their cooperative 105 110

relation, and at the same time the box has a free slideable adjustment upon such brackets in the manner hereafter described.

As stated the brackets 4 are preferably bifurcated and have one apertured ear 5 upon each side of the ear 2, though obviously such bifurcation is not a material matter and may be omitted.

Where a gang-box 16 is employed containing a plurality of switches, not shown, the same form of supporting brackets, and the same adjustment of the box thereon are employed as above described.

Both forms of boxes, of course, have the common form of flush plate 17, and both forms of boxes 1 and 16 have the usual "knock-out" 18 for the switch-wires not shown.

The manner of employing my invention thus described is obvious and briefly stated is as follows: The operator first fixes the invention in position upon the laths 8, as shown in Fig. 1, with the outer edge of the box 1 adjusted outwardly far enough to leave plenty of room for the required thickness of the plastering 7, after which he adjusts the box inwardly by the rotation of the screws 10 until the ears 2 are brought firmly against the plastering, as shown by dotted outline in Fig. 2, after which the box is firmly secured in position by proper screws in the ears 2, after which the closing plate 17 is fixed in position in the usual manner by the screws 19. As it is well known that the inner face of the plate 17 is recessed to receive the ears 2 it is evident that when the box 1 is adjusted to its position the plate 17 will rest squarely against the plastering without the necessity of any blocking out by the use of washers or other means. It is also evident that when my invention is mounted in old work, or walls already plastered, it is a great convenience, and makes a much neater job to be able to thus adjust the switch box to the thickness of the plastering.

It is obvious that in the use of my invention an adjustment of the switch box to com-

pensate for different thicknesses of plastering, is secured, without disturbing the supporting brackets therefor, and that the means for making such adjustment is conveniently accessible to the operator.

Having thus described my invention and the manner of employing the same, what I desire to secure by Letters Patent is:

1. An adjustable switch box consisting of a plurality of fixed brackets having their inner ends provided with screw-threaded openings, and having a longitudinal slot between their ends, a switch box horizontally adjustable between the brackets, screws fixed in the sides of the box and in the said slots to secure the box and brackets in their operative relation, and a plurality of adjusting screws operatively connecting the box with the brackets.

2. A switch box; a pair of oppositely arranged brackets between which the box is adjustably mounted; and adjusting screws loosely mounted in the inner face of the box and having a screw-threaded connection with the brackets.

3. In an adjustable switch box, fixed brackets in approximately vertical alinement and horizontal arrangement; a switch box horizontally adjustable on the said brackets; means for securing the box and brackets in their operative relation; and adjusting screws operatively connecting the inner face of the box with the rear ends of the brackets.

4. A horizontally adjustable switch-box; fixed brackets between which the interposed switch-box is slidably mounted; means for securing the switch-box and the brackets in their proper working relation; and means for imparting to the switch-box its horizontal adjustment; said means being operatively supported in the inner face of the box.

Signed by me at Fort Wayne, Allen county, State of Indiana, this 11th day of October, 1909.

EDWARD H. KRUSE.
